PROPELLED GLIDER

Sid Noble, Levittown, N. Y., assignor to Ideal Toy Corporation, Hollis, N. Y., a corporation of New York

Application March 18, 1958, Serial No. 50,083

Term of patent 14 years

(Cl. D34—15)

I claim:

The ornamental design for a propelled glider, as shown.
